UNITED STATES PATENT OFFICE.

SVEN JULIUS STRID, OF CHICAGO, ILLINOIS, ASSIGNOR TO FRED MATHEWS, OF CHICAGO, ILLINOIS.

Mounting for Brake Gears.

Application filed August 5, 1925. Serial No. 48,426.

To all whom it may concern:

Be it known that I, SVEN JULIUS STRID, a citizen of the United States, and a resident of Chicago, in the county of Cook and 5 State of Illinois, have invented certain new and useful Improvements in a Mounting for Brake Gears, of which the following is a full, clear, and exact description, such as will enable others skilled in the art to make and 10 use the same.

My present invention relates to means for mounting a brake operating gear at the end of a railway car, and it has more particular reference to a mounting that may be 15 readily attached to a car end-sill of channel-section. With the principles of the present device the mounting may be readily secured to the end-sill whether the channel has its flanges extending outwardly or inwardly 20 with respect to the car, and the mounting structure is firmly braced against the stress incident to the pull of the take-up chain of the brake-mechanism so that the mounting and gears are not liable to become loosened 25 or accidentally detached. I do this by providing an abutment or stop on the casting forming a part of the mounting which stop element contacts the outer surface of the web of the sill and by installing a reinforcement 30 gusset that projects transversely from the rear of the sill to which inwardly extending portions of the casting are secured.

I prefer to carry out my invention and to accomplish the several objects thereof in substantially the following manner, reference being made to the accompanying drawings that form a part of this specification.

In the drawings:—

Figure 1 is a top plan of the mounting structure secured to an end-sill of channel section with the flanges projecting inwardly.

Figure 2 is a right-hand end view of the structure with the sill in vertical transverse section.

Figure 3 is a vertical front view of the structure shown in the preceding figures.

Figure 4 is a view similar to Fig. 1 showing the application of the mounting to an end-sill having channel section and with the flanges projecting outwardly, the sill and gusset being in horizontal section.

Figure 5 is a right-hand end view of the structure with the sill in vertical section and the bottom casting omitted.

Figure 6 is a vertical front view of the 55 mounting detached from the sill.

The drawings illustrate typical or preferred embodiments of my invention, and so far as practicable I have employed similar reference characters to designate like parts 60 wherever the same appear throughout the several views.

The sill at the end of the car, in Figs. 1, 2, and 3 is a channel beam with its web 10 vertically disposed and with the lateral top 65 and bottom flanges 11 and 12 extended inwardly or towards the center of the car. Secured to the inner face of this sill and extending longitudinally of the car is a triangular shaped gusset 13 formed from a 70 metal plate its vertical, horizontal, and inclined edges provided with lateral flanges 14, 15, and 16 respectively, for the purpose of strengthening the gusset, said vertical flange 14 being riveted or otherwise secured to the 75 web of the sill and the horizontal flange 15 resting upon and extending inwardly from the bottom flange 12 of the sill.

The mounting structure in which the gear members are journaled comprises top and 80 bottom castings that provide bearings for the respective rotative members of the gearing. The top casting consists of a horizontally disposed rectangular shaped plate 17 that is secured to the under side of the lower 85 flange 12 of the sill and projects outwardly therefrom, and intermediate its edges it is provided with upstanding stops 18, 18, upon its upper surface that are each reinforced by inclined webs 19, 19, so as to brace said 90 stops against the outer front surface of the web of the sill along the lower edge thereof. Extending inwardly from the opposite edge of the plate 17 is a tapered horizontal extension 20 that is approximately the length of 95 the horizontal flange 15 of the gusset and is riveted or otherwise secured to said flange adjacent the inner end thereof. Thus the top casting is braced against the longitudinal pull of the brake gear winding chain, which 100 exerts a stress longitudinally of the car, and it is reinforced against tilting by the provision of the gusset plate 13.

The end edges of the plate 17 are provided with lateral depending flanges 21, 21, that 105 over-lap and are secured to lateral upstanding flanges 22, 22, upon the adjacent end edges of the horizontal plate 23 of the bot-

tom casting. Formed integral with the plate 23 of the bottom casting is a bracket arm 24 that extends inwardly longitudinally of the car and in a plane below the plane of the plate 23, as will be seen in Fig. 2 of the drawings. This bracket arm is parallel with, but slightly lower than, the tapered extension 20 of the plate 17 of the top casting and affords therewith a dependable means 10 for supporting and journaling one of the elements of the gearing device.

In Figs. 4, 5, and 6 the web 10 of the sill is vertically disposed but the lateral top and bottom flanges 11 and 12 project outwardly of the car instead of inwardly as heretofore described so that it is necessary to slightly alter the construction of the bracing members. The plate 17 of the top casting fits against the under surface of the lower flange 12 of the sill and said plate is provided with a stop or abutment in the form of a shoe 25 that extends longitudinally of the plate and is vertically positioned so as to fit against the web of the channel sill. The shoe has an undercut or recessed portion 26 that is slightly inclined and is spaced a slight distance from the plate so that the lower flange 12 of the sill may be inserted therein as will be seen 20 in Fig. 5. The web of the shoe 25 is riveted or otherwise suitably secured to the web of the sill and there are bracing struts or fins 27 extending from the upper edge portion of the shoe in an outward direction along the undercut or recessed portion and on the upper surface of the plate 17 so as to strengthen the structure. The gusset 13 and the remaining portions of the top and bottom castings are substantially the same as 30 the corresponding parts in the first described form of the structure, and therefore need not be again described.

What I claim as new is:—

1. In combination with a car end-sill of 45 channel section, of a gusset secured to the end-sill and extending inwardly therefrom longitudinally of the car, a top casting consisting of a plate disposed underneath the lower flange of the sill, an extension projecting inwardly from said plate and con-

nected to said gusset, an upstanding member on said plate outside said sill and engaged therewith and a bottom casting connected to said top casting and cooperating therewith to mount a gearing mechanism between the 55 same.

2. In combination with a car-end sill of channel section, of a gusset secured to the end-sill and extending inwardly therefrom longitudinally of the car, a plate positioned 60 against the lower flange of said sill and extended outwardly beyond the vertical plane of the web of the sill, a member projecting from said plate horizontally inwardly of the car and secured to the gusset, an upstanding stop positioned against the side of the sill opposite said gusset, a bottom plate spaced from said top plate and connected therewith, and an arm extending inwardly from said bottom plate and disposed parallel with said horizontally projecting member.

3. A mounting for railway car brake-gearing comprising top and bottom castings, said top casting consisting of a horizontally 75 disposed plate, a tapered extension projecting from one of the longitudinal edges thereof, and a stop projecting upwardly from said plate intermediate its sides and end, said extension and stop formed integral with said plate, said bottom casting consisting of a plate spaced from and connecting with the first named plate, and an integral bracket arm projecting from one of the longitudinal edges thereof and positioned 85 parallel and below the extension of said top plate.

4. In a mounting for railway car brake-gearing a plate of substantially rectangular shape adapted to be secured to the lower edges of the car end-sill, an integral extension projecting from one of the longitudinal edges of said plate and extending inwardly of the sill, and an integral stop projecting from the plate in a plane at an 90 angle to the plane of said extension.

Signed at Chicago, in the county of Cook, and State of Illinois, this 7th day of July, 1925.

SVEN JULIUS STRID.
